SIGNALING METHOD AND SYSTEM.

Application filed December 31, 1920. Serial No. 434,192.

This invention relates to signaling systems and more particularly it relates to methods and systems for secret signaling.

One of the objects of this invention is to provide a signaling method and system by means of which signals such as telephone signals can be transmitted without any danger of the signals being intelligently received by persons not equipped with the special receiving apparatus of this invention.

The preferred embodiment of this invention by means of which the above object is obtained employs two separate signaling channels and the signaling is obtained by switching the sending and receiving instruments synchronously from the channel to the other at irregular intervals in accordance with a code and at such a speed that the portions transmitted solely by each channel are unintelligible. If desired a source of meaningless signals can at the same time be switched so as to be always on the line which is not being used for the transmission of the true signals. Still further difficulty in deciphering the messages impressed upon the signaling channels can be obtained by having the intensity of the meaningless signals or noise vary in intensity with the true signals.

This invention will be better understood by having reference to the following detailed description taken in connection with the accompanying drawings in which Figure 1 represents an embodiment of this invention in which mechanical switching means are employed for switching the source of signals from one signaling channel to another, Figure 2 represents in perspective the mechanical switching means employed in Figure 1 and Figure 3 represents an embodiment of this invention in which the switching from one signaling channel to another is accomplished by the intermediation of vacuum tubes.

Referring to Figure 1 the signaling system disclosed therein comprises two lines 10

and 11 which serve to inter-connect the combined transmitting and receiving stations 12 and 13. The station 12 comprises an ordinary subscriber set including a transmitter 14 and a receiver 9. By a mechanical switching arrangement for alternately connecting contacts 21 and 22 to contacts 23 and 24, signals from the transmitter 14 are adapted to be impressed at one time upon line 10 and at another time upon line 11. The same switching means also operates to associate the source of meaningless signals or noise 15 with lines 10 and 11 in such a way that the noise currents are at any particular time impressed on that line which is not associated with the transmitter 14. At any particular instant therefore, line 10 for example, will contain signaling currents, while line 11 will contain noise currents; and at another instant, determined by the mechanical switching means, line 11 will contain the signaling currents and line 10 will contain the noise currents.

The switching arrangement by means of which the two lines 10 and 11 are alternately connected to the transmitter 14 and alternately connected to a source of noise 15 is shown in detail in Figure 2 in which 16 represents an endless perforated tape which is adapted to travel over two rollers 17 and 18. These two rollers have spaced pins in their periphery which co-operate with slots in the tape 16 whereby the tape is adapted to be continuously moved by the motor 48; 19 is a block of conducting material which by a lead 20 is adapted to be connected to contact 23 of Figure 1. Positioned in the groove formed in block 19 and insulated therefrom is a second block for conducting material 26 which by a lead 27 is adapted to be connected to contact 24 of Figure 1. As shown, tape 16 is adapted to pass over the upper surface of blocks 19 and 26 and the tape 16 is provided with a plurality of slots 30, each of which when passing over blocks 26 and 19 allows a pin 31 to contact with block 19 and allows a pin 32 to contact

with block 26. These pins 31 and 32 by leads 25 and 33 are adapted to be connected to contacts 21 and 22 respectively of Figure 1. Tape 16 also contains a plurality of slots 35 each of which when passing over blocks 19 and 26 allows pin 36 to contact with block 26 and pin 37 to contact with block 19. Pins 36 and 37 by leads 25 and 33 are adapted to be connected to contacts 21 and 22 respectively. It is, therefore, evident that when a slot 30 allows pins 31 and 32 to contact with blocks 19 and 26 respectively, contact 21 of Figure 1 will be connected to contact 23 and contact 22 will be connected to contact 24. This will connect winding 40 of transformer 41 in series with winding 42 of transformer 43 and will connect winding 44 of transformer 45 in series with winding 46 of transformer 47. With such an arrangement it is evident that signals from the transmitter 14 by transformers 41 and 43 will be impressed on line 10 and noise currents from source 15 by transformers 45 and 47 will be impressed on line 11. If on the other hand, a slot 35 happens at a particular instant to allow pins 36 and 37 to contact respectively with blocks 26 and 19, contact 21 will then be connected to contact 24 and contact 22 will be connected to contact 23. This connects winding 40 in series with winding 46 so that signals from the transmitter 14 are impressed on line 11 and connects winding 44 in series with winding 42 so that the noise currents are impressed on line 10.

The length of each slot 30 and 35 may be varied in any way desired to produce an irregular switching of the talking currents from one line to the other. In some cases it may be found desirable to have two slots 30 for example, follow each other directly without the intervention of a slot 35 in passing from one of these two adjacent slots to the other. This will give rise to a small click in the outgoing line which however, will not indicate a switching of the signals from one line to the other. These false clicks obtained will render still more difficult the intelligible detection of the signals by any one not provided with the special receiving apparatus hereinafter described.

The difficulty of deciphering the message without special receiving apparatus may be still more greatly enhanced by having the noise currents vary in intensity with the strength of the telephone signals from transmitter 14. As shown in Fig. 1, transmitter 14 is also connected by a transformer 50 to the input circuit of a vacuum tube 51. The output circuit of the tube 51 includes a source of voltage 49 in series with a resistance 53 which is shunted by a path including a condenser 52. Resistance 53 is also included between the control electrode 54 and the cathode 55 of an amplifier 56. The out-

put circuit of tube 51 by a transformer 45 is adapted to be associated with the outgoing lines 10 and 11.

Tube 51 and its associated apparatus should be so adjusted that for zero input potentials from source 14 substantially all of the electrons emitted by the cathode 48 of tube 51 pass to its anode. The effect of an alternating current voltage from source 14 can cause therefore only a decrease in the output current of tube 51 and the amount of the decrease will be proportional to the intensity of the currents from source 14. The shunt path including condenser 52 should have such an impedance as to prevent currents of speech frequencies from passing through the resistance 53, while still allowing the direct current passing through the resistance to decrease, each time a word is spoken in transmitter 14, an amount proportional to the intensity of the currents produced thereby. Since resistance 53 has its negative end connected to control electrode 54 so that a decrease in the I R drop in resistance 53 makes control electrode 54 less negative, it follows that the value of the output current of tube 56 will be directly proportional to the strength of the signals from source 14. The potential of control electrode 54 by a transformer 57 is also varied in accordance with currents from the source of noise 15. Transformer 45 therefore is adapted to impress on the outgoing lines noise currents varying in intensity with the intensity of the signals from source 14.

If desired the I R drop through resistance 53 may be made such that in the absence of signals from source 14, the space current of tube 56 is zero even for maximum positive values of the voltages received from source 60. In such a case noise currents from source 15 will be impressed on the line only when transmitter 14 is actuated.

The source of noise currents may be of any suitable type, for example, it may be a telephone transmitter 60 which is associated with a phonograph 61. The sounds impressed on the transmitter 60 by phonograph 61 may be from a record produced from a tone of a single frequency or may be a meaningless noise of any type. It is preferable however, that the record for phonograph 61 be made such as to have in it irregular clicks which sound like the clicks produced by the switching arrangement of Figure 2, so that it will be impossible for an observer listening in on both lines 10 and 11 to determine just what clicks heard were the clicks indicating a switching of the speech from one line to another.

Station 13 comprises apparatus similar to that already described for station 12. Switching means synchronized by apparatus not shown, with the switching means of station 12 are provided for connecting contacts

65, 66, 67 and 68 in such a manner that a receiver 69 is responsive to currents in line section 10 when the signals from the transmitter 14 are impressed thereon and is responsive to currents in line 11 when signals from the transmitter 14 are on line 11.

Transmission from station 13 to station 12 may be obtained in a manner similar to that described for transmission in the opposite direction. The transmitter 70 by the switching apparatus will be alternately connected to line sections 10 and 11 and the switching apparatus of station 12 operating in synchronism therewith, will make the receiver at 14 responsive always to that line on which the signaling currents happen to be.

The system illustrated in Figure 3 is somewhat similar to that of Figure 1 except that the switching from one line section to the other is obtained through the intermediation of vacuum tubes. 80 and 81 are two vacuum tube repeaters connected in the so-called push-pull relation. The input circuit of tube 80 includes the secondary winding of a transformer 82, a battery 83 and a resistance 84; and the input circuit of tube 81 includes the secondary winding of the transformer 85 and a resistance 86. The cathodes of tubes 80 and 81 by a lead 102 are connected between resistance 84 and 86. The primaries of transformers 82 and 85 are associated with the telephone transmitter 87. Resistances 84 and 86 are adapted to be connected in series with a battery 88 when a perforation in tape 89 allows pin 90 to contact with block 91. Battery 88 of course, is not in circuit with the resistances 84 and 86 when perforations are not passing between contacts 90 and 91.

The batteries 83 and 88 should have such relative values that when the connections for battery 88 are broken battery 83 is of such a value and so poled that grid 93 of tube 80 has such a negative potential that the space current of tube 80 is zero. When connections are made for battery 88 however, the resultant drop in potential across terminals of resistance 84 should be such as to make the potential of grid 93 such as to allow normal space current to flow in tube 80. Since battery 83 is not included in the input circuit of tube 81 it follows that normal space current will flow through tube 81 as long as the connections for battery 88 are broken. When however, the connections for battery 88 are made it will be seen that the drop in potential across the terminals of resistance 86 can be made such that the grid of tube 81 will be made so negative as to reduce to zero the space current of tube 81. Thus it will be seen that as tape 89 by suitable means is pulled between contacts 90 and 91, tube 80 will be operative when contact is made between contacts 90 and 91, while tube

81 is inoperative in this condition; and tube 81 will be operative and tube 80 inoperative whenever the connection between contacts 90 and 91 is broken.

The output circuit of tube 80 by transformer 95 is connected to the mid points of the line windings of a three winding transformer 96 so that when tube 80 is operative currents from transmitter 87 will be amplified by tube 80 and impressed on line 97. 75 Similarly, the output circuit of tube 81 by a transformer 98 is connected to the mid points of the line windings of a three limbed transformer 99 so that when tube 81 is operative amplified currents from transmitter 87 80 are amplified by tube 81 and impressed by transformer 98 upon the line 100. It follows, therefore, as the tape 89 is pulled between contacts 90 and 91 that the signals from transmitter 87 will be switched from 85 line section 97 to line section 100 and vice versa in accordance with any code represented by the arrangement of the slots in tape 89.

In order to connect the source of noise currents 101 to that line at any particular instant not employed in the transmission of signals from transmitter 87, two other vacuum tubes 103 and 104 are provided, which are connected in the so-called push-pull relation. The input circuit of tube 103 includes the secondary winding of a transformer 105 and also by lead 106 includes battery 83 and resistance 84. The input circuit of tube 104 includes the secondary 95 winding of transformer 108 and by lead 109 also includes resistance 86. Since tube 103 contains in its input circuit battery 83 and resistance 84, it follows that tube 103 is operative when tube 80 is operative and is inoperative when tube 80 is inoperative. The output circuit of tube 103 by a transformer 110 is therefore connected to the mid points of the three limbed transformer 99. At the time tube 80 is impressing the signal currents upon line section 97, tube 103 is impressing on line section 100 the noise currents from source 101. 100

Since tube 104 also includes in its input circuit resistance 86, it follows that tube 104 115 will be inoperative or operative dependent on the same conditions as in the case of tube 81. The output circuit of tube 104 by a transformer 107 is therefore connected to the mid points of the line windings of transformer 96 so that tube 104 will serve to impress the noise currents upon line section 97 at the time tube 81 is impressing the true signalling currents upon line 100. 120

If desired the strength of the noise currents from source 101 may be varied, as in Fig. 1; in accordance with the strength of the signals from transmitter 87. Block 78 is intended to represent tubes and associated apparatus similar to tubes 51, 56, etc., 130

of Fig. 1. Transformer 74 would then correspond to transformer 50 of Fig. 1.

The receiving apparatus for receiving signals from transmitter 87 comprises two tubes 109 and 110 connected in the push-pull relation. The input circuit of tube 109 includes the secondary winding of a transformer 111 and also includes a resistance 112 and a battery 113. The input circuit of tube 110 includes the secondary winding of a transformer 114 and a resistance 115. The primary winding of transformer 111 is in circuit with the third winding of the three limb transformer 117, while the primary winding of transformer 114 is in circuit with the third winding of the three limb transformer 118. Resistances 112 and 115 are adapted to be connected in circuit with battery 120 when the perforations in tape 121 allow contact to be made between contacts 122 and 123. By suitable mechanism, tape 121 is driven in synchronism with tape 89 and if the perforations in the tapes are similar, it follows that tube 109 will be operative when tube 80 is operative and tube 110 will be operative when tube 81 is operative. Tube 109 which by a connection previously traced is adapted to receive currents from line 97, will be operative to receive these currents at the time when tube 80 is operative to impress currents on line 97 from source 87. Similarly tube 110 will be operative to receive currents from line 100 when tube 81 is operative to impress currents from transmitter 87 upon line 100. Since the receiver 124 by transformers 125 and 126 is responsive to variations in the currents of the output circuits of both tubes 109 and 110, it follows that receiver 124 will receive a faithful copy of signal current from transmitter 87.

The apparatus described above serves to transmit signals from transmitter 87 by lines 97 and 100 to the receiver 124. It is evident that transmitting apparatus similar to that associated with transmitter 87 may be located at the station where receiver 124 is located for transmitting signals in the opposite direction from that above described. Block 135 is intended to represent the transmitting apparatus of this invention connected to the mid points of the line windings of the transformers 117 and 118 for impressing the signals upon lines 97 and 100. Suitable receiving apparatus for these signals may be provided at block 136. Blocks 137 and 138 represent suitable artificial lines for balancing line 100 whereby signals from transmitter 87 are not impressed on the local receiving apparatus and whereby signals from source 135 are not received by receiver 124. Blocks 139 and 140 represent similar artificial lines for line 97.

It is evident of course, that the receiver 124 will not receive the noise currents from source 101, since at the time noise currents

are impressed on the line 100 the tube 110 is inoperative and at the time the noise currents are impressed on line 97 the tube 109 is inoperative. It is also evident that a similar observation applies to the system of Figure 1 since the switching arrangement at station 13 operates to connect at any particular time the line bearing the noise currents to the output circuit of the tube 130. As is well known tubes of the type disclosed are unidirectional in character and therefore currents impressed on the output circuit of tube 130 cannot find their way back by any connection whatsoever to the receiver 69.

It is to be understood that the arrangement above described may be variously modified without departing in any way from the spirit of this invention as defined in the appended claims. For example, this invention is not limited to the employment of only two channels between the transmitting station and the receiving station, since the invention broadly consists in transmitting portions of the signal over a plurality of channels or by a plurality of carriers, successively or in any arbitrary order desired.

What is claimed is:

1. The method of signaling in which a plurality of signaling paths are employed to transmit signals in one direction, which comprises automatically switching at short intervals the signaling source from one of said paths to another and similarly switching a source of noise to a path that at any particular instant is not employed in the transmission of said signals.

2. The method of signaling in which two signaling paths are employed to transmit signals in one direction, which comprises automatically switching the signaling source from one path to the other alternately in accordance with a code, and simultaneously switching a source of noise to that path at any particular instant not employed in the transmission of the signals.

3. A signaling system comprising a plurality of channels, signal transmitting apparatus, signal receiving apparatus, means for simultaneously switching at short intervals said transmitting and receiving apparatus from one of said channels to another, to enable signals to be transmitted from said transmitting apparatus to said receiving apparatus, and means coordinated with said switching means for transmitting waves over one of said channels which at the time is disconnected from said transmitting and receiving apparatus.

4. The method of signaling in which a plurality of signaling paths are employed to transmit signals from a signaling source, which comprises switching at short intervals the signaling source from one of said paths to another, simultaneously switching a source of noise to a line at any particular

- instant not employed in the transmission of said signals, and varying the intensity of said noise in accordance with the intensity of said signals.
5. In a signaling system having transmitting and receiving stations, a plurality of transmission channels between said stations, a source of signal waves at said transmitting station, a signal receiver at said receiving station, means for operably associating said source of waves with said transmission channels singly and in succession at pre-determined intervals, means for simultaneously shifting the said receiver at the same intervals into operative association with the said channels whereby the receiver is associated during each interval with the same channel as said source of waves, and means coordinated with the means for shifting the associations of said source of waves and said receiver with said channels for sending other waves unrelated to said signal waves over one of said channels which is at the time out of operative association with said source of waves and receiver.
6. The method of signaling, in which a plurality of carriers are employed between stations, which comprises automatically transferring the signals from one channel to another at irregular intervals, and similarly transferring noise currents from one channel to another at irregular intervals in such a manner that the signaling and noise currents at any particular instant are carried by different channels.
7. The method of signaling employing a plurality of carriers between stations, which comprises transferring the signals from one channel to another at irregular intervals, transferring non-signaling currents from one channel to another in such a manner that the signaling and non-signaling currents at any particular instant are carried by different channels, and controlling the intensity of the non-signaling currents in accordance with the intensity of the signals.
8. A signaling system comprising a line, a source of audio frequency signals of varying intensity, a source of audio frequency noise currents, and means for impressing on said line currents from said source of noise varying in intensity in accordance with the audio frequency signals.
9. A receiving system comprising an incoming line, two repeaters each having input and output circuits, each of said input circuits having portions in common and other portions individual to each repeater, and means for connecting an individual portion of each input circuit to said incoming line, and means for rendering said repeaters alternately operative to repeat signals from said line.
10. In combination, two incoming lines, means for alternately applying two currents of different character to each of said lines, current of only one character to one line at a time, and a receiving system comprising two repeaters each having an input circuit and an output circuit, each of said circuits having portions common to both repeaters and portions individual to each repeater, means for connecting an individual portion of each input circuit to a different one of said incoming lines, and means associated with the individual portions of the input circuits of said repeaters for alternately rendering said repeaters inoperative to repeat one of said currents of different character from said lines.
11. In a signaling system, two repeaters, each having an input circuit and an output circuit, each of said circuits having portions common to both repeaters and portions individual to each repeater, an impedance in the individual portion of each input circuit, a branch path connecting the non-adjacent terminals of said impedance, said path including a source of voltage, and means for making and breaking the connections to said source.
12. In combination, two repeaters each having input and output circuits, said input circuits having certain portions in common and certain portions individual to each repeater, means for impressing signals on the individual portion of one input circuit, means for impressing signals on the individual portion of the other input circuit, and means for alternately rendering said repeaters inoperative.
13. In combination, two repeaters each having input and output circuits, said input circuits having certain portions in common and certain portions individual to each repeater, means for impressing signals on the individual portion of one input circuit, means for impressing signals on the individual portion of the other input circuit, one of said repeaters being normally inoperative, and means for rendering said last mentioned repeater operative at times.
14. In an electric system, two repeaters each having input and output circuits, said input circuits having certain portions individual and other portions common to each repeater, two signal lines, a balancing network for each of said lines, a transformer having one winding in circuit with one of said balancing networks, a second winding in circuit with the corresponding line, and a third winding, a similar three winding transformer for said other line, connections between the individual portion of one of said input circuits and one of said third windings, and connections between the individual portion of the other input circuit and said other third winding.
15. In an electric system, two repeaters each having input and output circuits, each

- of said input circuits having portions in common and other portions individual to each repeater, a source of signals, means for impressing said signals at times upon the individual portion of one of said input circuits, and means for impressing at other times said signals upon the individual portion of the other input circuit, and means for alternately rendering said repeaters inoperative.
16. In an electric system, a plurality of vacuum tubes, each having an anode, a cathode, and a control electrode, a source of voltage, a resistance, a connection between one of said anodes and its corresponding cathode comprising said source and said resistance, a condenser of low impedance to currents of speech frequencies in shunt to said resistance, connections whereby the drop in potential across the terminals of said resistance is impressed between the control electrode and the cathode of a second vacuum tube, a source of variable currents, and means for impressing said currents between the control electrode and the cathode of said second vacuum tube.
17. In combination a vacuum tube having an output circuit, an impedance in said output circuit whereby a drop of potential across the terminals of said impedance is produced by the space current of said tube, a second vacuum tube having input terminals and an output circuit, said impedance being connected between said input terminals, said resistance having such a value that the normal direct current flowing through said impedance produces a potential difference between said input terminals sufficient to reduce substantially to zero the output current of said second tube.
18. In combination a vacuum tube having an input circuit and an output circuit, means for supplying signals of speech frequencies to said input circuit, a resistance in said output circuit, a receiving device, connections from said resistance to said receiving device, and means for substantially preventing currents of speech frequencies from passing through said resistance.
19. The method of producing a direct current corresponding to the intensity of voice currents which comprises rectifying said currents and filtering out the voice frequencies in the rectified currents.
20. In a secrecy system, a signaling channel, a source of signaling currents, a source of non-signaling currents containing frequencies present in and essential to said signaling currents, means for applying currents from said sources alternately to said channel, and means at the receiving end of said channel for separating said signaling currents from said non-signaling currents.
21. In a secrecy system, a signaling channel, a source of signaling currents, a source of non-signaling currents containing frequencies present in and essential to said signaling currents, means for applying currents from said sources alternately to said channel, and means at the receiving end of said channel for separating said signaling currents from said non-signaling currents.
22. In a secrecy system, a plurality of signaling channels, a source of signaling currents, a source of non-signaling currents containing frequencies present in and essential to said signaling currents, means for applying currents from said sources alternately to each of said channels, and means at the receiving ends of said channels for separating said signaling currents from said non-signaling currents and for combining the portions of said signaling currents received from said channels.
23. In a secrecy system, a plurality of signaling channels, a source of signaling currents, a source of non-signaling currents containing frequencies present in and essential to said signaling currents, means for applying currents from said sources alternately to each of said channels, and means at the receiving ends of said channels operating synchronously with said first recited means for separating said signaling currents from said non-signaling currents and for combining the portions of said signaling currents received from said channels.
24. In a transmission system, the combination with a source of waves to be repeated, of a transmission path including a space discharge device having a grid, means for controlling the transmission characteristics of said device for waves from said source comprising a source of control waves of varying amplitude, a rectifier for rectifying said waves of varying amplitude to produce a varying direct current voltage, and means to utilize said voltage for polarizing the grid of said discharge device.
25. In a transmission system, a space discharge device having a grid, a source of waves connected to the grid of said device to be repeated by said device and a control system for said discharge device comprising a source of waves of varying amplitude, a rectifier for rectifying said waves to produce a direct current of varying magnitude, a resistance connected in the path of said direct current, and a tap from said resistance to the grid of said device.
26. The method of rendering signals unintelligible which comprises impressing noise currents on a signaling channel and varying the amplitude of said noise currents in response to variations in the amplitude of the signal currents.
27. The method of controlling an amplifier which comprises rectifying speech cur-

rents and varying the transmission efficiency control electrode in accordance with the of said amplifier in accordance with the variations of the rectified currents. variations of the rectified currents.

28. The method of changing the amplification of an amplifier having a control electrode which comprises rectifying speech currents and varying the potential of said

In witness whereof, I hereunto subscribe 10 my name this 29th day of December A. D., 1920.

RALPH V. L. HARTLEY.

Certificate of Correction.

It is hereby certified that in Letters Patent No. 1,606,763, granted November 16, 1926, upon the application of Ralph V. L. Hartley, of East Orange, New Jersey, for an improvement in "Signaling Methods and Systems," an error appears in the printed specification requiring correction as follows: Page 2, line 66, for "tube 51" read *tube 56*; and that the said Letters Patent should be read with this correction therein that the same may conform to the record of the case in the Patent Office.

Signed and sealed this 21st day of December, A. D. 1926.

[SEAL.]

M. J. MOORE,
Acting Commissioner of Patents.
